UNITED STATES PATENT OFFICE.

GEORGE AMHURS MULLINS, OF WOODVILLE, WEST VIRGINIA, ASSIGNOR OF ONE-HALF
TO D. C. MULLINS, OF WOODVILLE, WEST VIRGINIA.

MACHINE FOR SAWING STAVES.

1,118,569.

Specification of Letters Patent. Patented Nov. 24, 1914.

Application filed May 25, 1914. Serial No. 840,932.

To all whom it may concern:

Be it known that I, GEORGE AMHURS MULLINS, a citizen of the United States, residing at Woodville, in the county of Lincoln and State of West Virginia, have invented certain new and useful Improvements in Machines for Sawing Staves, of which the following is a specification, reference being had to the accompanying drawings.

10 This invention relates to certain improvements in machines for sawing staves and has relation more particularly to a machine of this general character wherein the carriage for holding the work is manually operated 15 relative to the cutting member; and the object of the invention is to provide a device of this general character having novel and improved means whereby return movement may be imparted to the carriage, after a 20 cutting operation, in substantially an automatic manner.

The invention consists in the details of construction and in the combination and arrangement of the several parts of my 25 proved machine whereby certain important advantages are attained and the device is rendered simpler, less expensive and otherwise more convenient and advantageous for use, all as will be hereinafter more fully 30 set forth.

The novel features of the invention will be carefully defined in the appended claims.

In order that my invention may be the better understood, I will now proceed to describe the same with reference to the accompanying drawings, wherein—

Figure 1 is an elevational view of a stave cutting machine containing an embodiment of my invention; and Fig. 2 is a fragmentary view in top plan of one extremity of the track-way, with a part in section, illustrating in detail certain features of my invention as herein disclosed.

As disclosed in the accompanying drawings, 1 denotes a supporting frame of any ordinary or preferred construction on which is operatively supported the cylindrical saw 2 of any ordinary or preferred construction and the reciprocating carriage 3 which 50 may also be of any construction which best serves its purpose and which is adapted to be forced toward the cylindrical saw 2 manually, as is now generally done in machines of this general character.

55 Projecting upwardly from the frame 1

at the forward end of the track-way 4, on which the carriage 3 is adapted to travel, is the standard 5 having projecting forwardly therefrom the bolt members 6 and 7 disposed in vertical alinement and such bolt members are loosely directed through the elongated vertically disposed buffer member 8, the lower extremity whereof terminating in close proximity to the track-way 4 and adapted to be contacted with by the adjacent end of the carriage 3 when the same has been forced inwardly in order that the bolt or billet 9 of wood operatively engaged with the carriage 3 may be properly operated upon by the cylindrical saw 2. The bolt 7 has mounted thereon the expandable member 10, herein disclosed as a coil spring and this member is interposed between the buffer member 8 and the standard 5 whereby it will be readily perceived that the contact of the carriage 3 with the buffer member 8 will so compress the member 10 that when said carriage is released, the expansion of the member 10 will serve to automatically throw or return the carriage 3 toward the opposite end of a track-way 4 so that the bolt or billet may again be operated upon by the cylindrical saw 2.

To further increase the action of the buffer member 8, I find it of advantage to have the uppermost bolt member 6 projected forwardly of the buffer member 8 and having its free extremities provided with an enlargement 11, and interposed between such enlargement 11 and the upper extremity of the buffer member 8 is an additional expandable member 12 also herein set forth as a coil spring surrounding the forward extremity of the bolt. The bolt 6 is also surrounded by an expandable member 10' interposed between the buffer member 8 and the standard 5 and serves as an equalizer spring whereby the buffer member 8 will be normally maintained in substantially a vertical position, as indicated in Fig. 1.

At the forward end of the frame 1 between the track-way 4, I position the bumper block 14 which is adapted to be engaged by the forward end of the carriage 3 when the same is being automatically returned under the influence of the buffer member 8. The block 14, as herein disclosed, is operatively connected with the upper end of the vertically disposed arm 16 hingedly connected at its lower end, as at 15, to a

horizontal beam 17 which is also engaged by the vertical member 18 depending from the frame 1. Slidably disposed through the vertical member 18 and the hinged arm 5 16 is the rod 19, the opposite ends whereof being provided with the enlargements 20, and interposed between each of the enlargements 20 and the hinged member 16 and the vertical member 18, respectively, are the 10 expansible members 21, herein disclosed as coil springs. By this arrangement, it will be seen that the block 14 serves as a buffer for the carriage 3 and its return movement and the tension thereon created by the 15 expansible members 21 serve to facilitate the forward movement of the carriage whereby it will be readily perceived that an increased number of reciprocations may be imparted to the carriage 3 in comparison with the 20 general method wherein the movements of the carriage are created manually.

From the foregoing description, it is thought to be obvious that a machine constructed in accordance with my invention is 25 of an extremely simple and comparatively inexpensive nature and is particularly well adapted for use by reason of the convenience and facility with which it may be assembled, and it will also be obvious that my invention 30 is susceptible of some change and modification without material departure from the principles and spirit thereof and for this reason I do not wish to be understood as limiting myself to the precise arrangement and formation of the several parts 35 herein shown in carrying out my invention in practice.

I claim:

1. In combination with a frame provided 40 with a track-way and a carriage mounted

for reciprocal movement upon said track-way, an upright carried by the frame adjacent one end of the track-way, bolt members projecting from the upper extremity of the upright and overlying the frame, an elongated buffer member operatively supported by the bolt members and having its lower extremity terminating in close proximity to the track-way, and expansible members carried by the bolt members and coacting with the buffer member for normally maintaining the lower extremity thereof in a position above the track-way and away from the upright. 45

2. In combination with a frame provided 55 with a track-way and a carriage mounted for reciprocal movement upon the track-way, a standard carried by the frame adjacent one extremity of the track-way, vertically alined bolt members carried by the upper extremity of the standard and overlying the frame, an elongated buffer member operatively engaged with the bolt members, an expansible member surrounding the lower bolt member and interposed between 60 the standard and the buffer member, a head carried by the outer extremity of the upper bolt member, an expansible member surrounding said upper bolt member interposed between the head and the buffer member, 65 and an equalizing expansible member surrounding the upper bolt member and interposed between the buffer member and the standard. 70

In testimony whereof I hereunto affix my 75 signature in the presence of two witnesses.

GEORGE AMHURS MULLINS.
